UNITED STATES PATENT OFFICE.

JOHN HENRY HINDLE AND THOMAS HINDLE, OF HASLINGDEN, ENGLAND.

SHEDDING MECHANISM FOR LOOMS FOR WEAVING.

Application filed August 31, 1927, Serial No. 216,678, and in Great Britain October 12, 1926.

This invention relates to a tappet or shedding motion for looms more particularly applicable to looms for weaving heavy multiple ply fabrics.

5 According to the invention the tappets or cams are mounted transversely, on a shaft or drum at right angles to the longitudinal axis of the loom, each tappet is machined from steel plate with a cam groove on both sides 10 and the tappet levers are mounted above and below the tappet shaft the upper levers engaging the end operated by the cam groove on one side of the tappet and the lower lever 15 engaging the end operated by the cam groove on the other side of the tappet, the frame carrying the tappets and levers constituting a separate unit capable of being detached from the looms.

The invention will be fully described with 20 reference to the accompanying drawings.

Fig. 1 is a front elevation.

Fig. 2 is a side elevation.

Fig. 3 is a side elevation of tappet or cam and tappet levers.

25 The tappets or cams A and the tappet levers B are mounted in a frame C and disposed transversely to the longitudinal axis of the loom and constituting a separate unit capable of being detached from the loom without disturbing or displacing other parts of the mechanism.

The tappets A are fitted on a central shaft D and drum d at right angles to the longitudinal axis of the loom rotating in bearings in 35 the frame C and driven by bevel gearing e on the end of the crank shaft E and spur gears d¹, d² on counter-shafts d³ gearing with pinion d⁴ mounted in bearings in the lower frame C¹ with suitable change wheels to vary the 40 speed of the tappets to suit requirements. The tappet levers B are pivoted on studs b which also serve as stays or distance pieces bolted between the frames C.

The frame C¹ is permanently bolted to the 45 loom gable C² and to the floor or sole plate and the tappet frame C stands upon the lower frames C¹ being detachably bolted thereto and to the loom gable C² to provide for its removal without disturbing the lower frame or 50 the counter-shafts and gears mounted therein.

Each intermediate tappet or cam A is ma-

chined from steel plate with cam grooves a on both sides that on one side to operate the upper set of tappet levers B and that on the other side to operate the lower set of tappet 55 levers B¹. The tappets A being machined from steel plate may be made very thin and set close together a washer or distance piece a¹ on the central drum separating one from the other.

60 Each tappet lever B—B¹ is constructed with a boss b¹ at its pivoted end and at or near its centre carries a bowl or runner b² to enter the cam groove a in one side of the tappet A the bowl being preferably mounted on ball 65 bearings.

The tappet levers B, B¹ pass between the tappets and to the free ends links and chains F are connected the chains passing over pulleys f along the top and bottom of the 70 loom to connect with the healds or shafts, the connections between the levers and chains being easily detachable.

By this construction the tappets A and 75 tappet levers B with their frame C and driving pinion d⁴ form a unit readily detachable and the number of tappets are reduced nearly by half so that for eight healds, five tappets suffice, three intermediate or central ones with two grooves each and two outside ones, 80 four tappet levers each being pivoted towards the upper part of the tappets and four towards the lower part.

What we claim as our invention and desire 85 to protect by Letters Patent is:—

1. A shedding motion for looms comprising 90 tappets, having cam grooves on both sides, mounted transversely of the loom, a shaft at right angles to the longitudinal axis upon which the tappets are mounted, tappet levers mounted above and below the tappet shaft, the upper levers engaging and being operated by the cam grooves on one side of the tappets, and the lower levers engaging and being operated by the cam grooves on the other side of 95 the tappets.

2. A shedding motion for looms as in claim 1 constructed as a separate detachable unit.

In testimony whereof we have hereunto set our hands.

JOHN HENRY HINDLE.
THOMAS HINDLE.
